CLAIM

I claim the ornamental design for stackable tool sorter, as shown and described.

DESCRIPTION

FIG. 1 is a top perspective view of a stackable tool sorter; FIG. 2 is a front view thereof; FIG. 3 is a rear view thereof; FIG. 4 is a top view thereof; FIG. 5 is a bottom view thereof; FIG. 6 is a right view thereof; FIG. 7 is a left view thereof; and, FIG. 8 is a bottom perspective view thereof.
The broken lines in the drawings illustrate portions of a stackable tool sorter which form no part of the claimed design.
